UNITED STATES PATENT OFFICE.

FRANK WEBB STOCKTON, OF CHICAGO, ILLINOIS.

TOWEL-CABINET.

1,240,620.

Specification of Letters Patent. Patented Sept. 18, 1917.

Application filed June 16, 1916. Serial No. 104,133.

To all whom it may concern:

Be it known that I, FRANK WEBB STOCKTON, a citizen of the United States, residing at Chicago, in the county of Cook and State 5 of Illinois, have invented new and useful Improvements in Towel-Cabinets, of which the following is a specification.

One of the objects of my invention is to provide an improved device for supplying 10 individual towels for public use, successively to respective users. Another object is to provide means in such device for the disposal of soiled towels. Another object is to provide, in such device, means tending to 15 prevent the misplacement of the towels before or after use. Another object is to provide in such device means tending to especially convenient use. Other objects will be evident hereinafter.

20 Referring to the drawings, Figure 1 is a perspective view of the device, containing a towel ready for use. Fig. 2 is a vertical, front-to-back, middle section of the same. Fig. 3 is a perspective view of a towel adapted 25 to use in this device. Similar numerals refer to corresponding parts throughout the several views.

The device comprises an upper receptacle 2 for containing clean towels 4; a lower receptacle 3 for containing soiled towels; and a retaining rod 1, extending from the upper receptacle to the lower receptacle. The upper receptacle is supported by means of the back portion 30. The towels are strung on 30 the retaining rod 1, and for this purpose each towel has at one edge a hole, which is reinforced by a gromet 7, the hole being large enough to allow the towel to be easily slipped along the rod. As shown at reference numeral 6, the lower end of the retaining rod 1 is bent forward and fits the hole made for it in such a way as to be secure against removal unless the rod 1 is drawn forward, in which case it can be slipped out. 45 As shown at 5, the upper end of the retaining rod is secured; and in this normal working position neither end of the rod can be removed.

In Figs. 1 and 2 the base of the clean- 50 towel receptacle 2 has a slot 9 cut through it, extending from the middle of the front of the base toward the back for about half the depth of the base. The upper portion of the retaining rod 1 extends horizontally, 55 front-to-back, parallel with the edges of this

slot, within the slot or slightly below it, the end of the rod being secured at 5.

A towel adapted for use with this cabinet, containing a slot through the base, is shown in Fig. 3. It has a tongue 10 attached to one 60 end. This tongue contains the hole, reinforced by gromet 7, for receiving the retaining rod. The clean towels rest upon the base of the receptacle 2 with their tongues extending downwardly through the slot 9 65 and retained by rod 1.

For public use, a large number, say one hundred, clean towels are stacked in receptacle 2 with their gromets strung on retaining rod 1. A person desiring to use a towel, 70 grasps the top towel, pulls it forward on the retaining rod in the direction indicated by the arrows to a position convenient for use, where it can be used for the hands or face. After use, the towel is released, and it drops 75 by its weight into the soiled-towel receptacle 3, all the while being retained by and following the course of the retaining rod 1.

In order to remove soiled towels from the cabinet and to replace clean ones, the retaining rod 1 is unlocked at 5 and is lifted out, the soiled towels slipping off the lower end. The retaining rod is then replaced in its lower fastening, shown at 6, and a bundle of 80 towels is suitably placed on the retaining rod 85 by way of its upper end. The upper end is then locked in place at 5.

While I have described particular constructions as specific embodiments of my invention, I desire not to be limited thereto. 90 What I claim and desire to secure by Letters Patent is:

1. In a device of the class described, a 95 towel support pierced by a slot which is adapted for the extension from above of a portion of a towel therethrough to a towel-retaining member below; and a towel-retaining member extending outwardly along the slot and below the surface of the towel support and then extending downwardly, constituting a suitable guide for a towel while in use, substantially as described.

2. In a device of the class described, a horizontal towel support pierced by a slot 105 extending from the front edge of said towel support backwardly through a considerable portion of said towel support, said slot being adapted for the extension from above therethrough of the tongue of a towel for attachment to a towel-retaining member below 110.

said towel support; and a towel-retaining member extending horizontally along said slot and below the same to a point allowing of convenient use of a retained towel and 5 then extending downwardly, constituting a suitable guide for a towel while in use, substantially as described.

3. In a device of the class described, a towel support pierced by a slot which is 10 adapted for the extension from above therethrough of the tongue of a towel for attachment to a towel-retaining member below; and a towel-retaining member extending

from a point below said towel support to a point allowing of convenient use of a retained towel, and then extending downwardly, said retaining member constituting a suitable guide for a towel while in use substantially as described. 15

In testimony whereof I have subscribed 20 my name.

FRANK WEBB STOCKTON.
